BENDING MACHINE

Ralph M. Shaw, Jr., Edgewater Park, N. J., assignor to Pedrick Tool & Machine Company, Philadelphia, Pa., a corporation of Pennsylvania

Application September 17, 1943, Serial No. 502,737

1 Claim. (Cl. 153—46)

1

This invention relates to machines useful in bending bars or tubes, and has reference more particularly to bending machines of the type disclosed in U. S. Patent No. 2,266,912, granted to me on December 23, 1941.

My present machine has for its chief aim to enable, through structural improvements and refinements such as hereinafter illustrated and described, fashioning in machines of the kind referred to, of straight bars or tubes into complete circles or even into spirals without incidental deformation of their original cross sectional configurations or marring of their surfaces.

How the foregoing desideratum as well as other objects and attendant advantages can be readily realized in practice will appear from the following detailed description of the accompanying drawings, wherein

Fig. 1 shows in top plan a bending machine conveniently embodying my present invention.

Fig. 2 is an axial sectional view of the machine taken as indicated by the angled arrows II—II in Fig. 1.

Fig. 3 is a perspective view of one of the die members of the machine.

Figs. 4 and 5 are views like Fig. 1 on a smaller scale showing successive steps in the bending.

Fig. 6 shows a complete circular loop formed in a tube after a few passes in the machine; and

Fig. 7 shows a spiral such as will result by continuing the bending after the stage shown in Fig. 6 has been reached.

Except as hereinafter particularly pointed out, the improved bending machine is generally like that disclosed in my above mentioned patent, said machine including a bed plate 10 whereinto is recessed a rotatable disk 11 with peripheral teeth 12 engaged by a driving pinion 13. Fixed in the bed plate 10 and passing through an axial opening in the disk 11 is a cylindric post 14 which is diametrically reduced at its top and there supports a stationary die member 15. Fulcrumed on the post 14 below the stationary die member 15 is an arm 16, which, adjacent its outer end, is releasably secured by a latch pin 17 to the top of the disk 11 so as to rotate with the latter. As shown, the arm 16 carries a follower roller 18 which is revolvably and axially free on a stud 19 capable of adjustment along a longitudinal slot 20 in said arm. The follower roller 18 bears against a straight elongate shoe 21 which constitutes the movable complementary or mating die member of the machine and cooperates with the stationary die member 15 in effecting the bending. The holder indicated at

2

22 for a tube T, which is to be bent, is supported by the bed 10 on the top edge margin thereof.

Instead of being circular as in the patent supra, the stationary die element 15 is in the form of a sector which comprehends an arc of less than 180°—to be more exact of about 135°—and which is keyed to the stud 14 at 23 so as to be readily removable for substitution of similar die members of different sizes and/or shapes.

Moreover, in accordance with my present invention, the stationary die member 15 has a relatively deep groove 25, in its arcuate edge portion which, in the illustrated instance is of U-shaped cross sectional configuration and, which, see Fig. 2, is inclined upwardly to the horizontal from its entrant end at 26 to its terminal end at 27. Also in accordance with my present invention the complementary movable die member or shoe 21 is of a length somewhat in excess of the arcuate peripheral extent of the stationary die member 15 and provided with a longitudinal ridge 28 at its inner side, said ridge being of a width to snugly engage within the groove 25 of said non-rotating die member. From Figs. 2 and 3 it will be noted that in the present instance the ridge 28 of the shoe 21 is concaved and with the rounded bottom of the groove 25 in the non-rotating die member 15 defines a die opening of circular cross section corresponding to that of the tube T.

The holder 22 is of novel construction in that it comprises a split clamp 30 with winged jamb nuts 31; and a supporting block 32 with a pendent stud 33 which slidably fits into a socket hole in the top of the bed plate 10, as well as with a vertical slot 34 for the free reception of a lateral stud projection 35 on the clamp 30. As a consequence of this construction, the holder 22 is free to swivel and to rise and fall during the bending while restraining endwise movement of the tube T; or, in other words said holder restrains the tube T.

The operation of the machine is as follows: In preparation for the bending the disk 11 is rotated to bring the arm 16 into the full line position P in Fig. 1; the bar or tube T is secured in the holder 22 so that the distance from the extended end E thereof to the entrant end 26 of the stationary die member 15 corresponds in length to the arcuate extent of the periphery of said die member; and the movable die member or shoe 21 is inserted between the tube T and the follower roller 18 as illustrated. With this preparation, the disk 11 is rotated in the direction indicated

by the curved arrow in Fig. 1 through an arc of 135° when the arm 16 will have reached the position P' in which it is indicated in dot-and-dash lines in said figure. As a consequence of the travel of the follower roller 18 in a circular orbit concentric with the arcuate edge of the stationary die member 15, the shoe 21 will assume different angular positions tangentially to said edge and cause the extended end portion of the tube T to be depressed into the groove 25 of said stationary die member. Due to the shaping of the opposing die surfaces and the manner of their interfitment, the original circular cross section of the tube T is preserved during the bending without attendant formation of "fins" or die marks thereon. Since the bending force or pressure is applied throughout the cycle at a tangential point which moves around the stationary die member 15, the shoe 21 will readily adapt itself to the inclination of the groove 25, in said die member, this action being facilitated by reason of the axial freedom of the follower roller 18 on its supporting stud 19 and by virtue of the ability of the holder 22 to swivel as well as to rise and fall in accommodating lateral movements of the restrained end portion of the tube T. With the first bend completed, the disk 11 is reversely rotated and returned to its original position P whereupon the bar or tube is shifted as shown in Fig. 4 by a distance corresponding in magnitude to the peripheral extent of the stationary die member 15 and again clamped by the holder 22. The above described cycle of the machine is then repeated to move the arm 16 from the position P to the position P' in Fig. 4 thereby adding another 135° bend to the bend made in the first pass of the tube T in the machine. After the formation of the second bend, the arm 16 is again returned to the position P as shown in Fig. 5 and the tube T once more shifted and re-clamped in the holder 22 for a third pass by which the arm 16 is a third time moved from the full line position to the dot-and-dash line position P'. By the last described pass still another 135° is added to the curvatures formed in the previous passes, so that somewhat more than a complete circular loop results as shown in Fig. 6. By further repetitions of the above procedure, it is obviously pos-

sible to fashion the tube into a coil such as shown in Fig. 7 which can be subdivided into a number of individual split ring blanks by cutting the same at one side along a line X—Y. After the cutting, the ends of the individual ring blanks are brought into line and welded or otherwise united to close the rings. The use of a stationary die of less than a half circle such as herein featured, is advantageous in that it permits ready removal of the work from the machine at any stage of the bending.

Solid bars of circular cross section of course lend themselves to ready bending in my improved machine in the form in which it is herein illustrated by way of example. Furthermore, by appropriately profiling the opposing faces of the cooperative die members 15 and 21 it will be apparent to those skilled in the art that my improved machine can be adapted for bending bars or tubes of other cross sectional shapes within the scope of the appended claim.

Having thus described my invention, I claim:

A machine for spirally bending bars, tubes or the like, comprising in combination a stationary die member in the form of a sector having a relatively deep inclined groove in its peripheral edge; a complementary movable die member in the form of a straight elongate shoe having a longitudinal ridge for snug engagement within the outer edge limits of the inclined groove of the stationary die member to jointly form an opening conformatory with the cross-section of the bar or tube to be bent; a holder comprising a split-clamp and a pivotal supporting-block, said split-clamp having a projection slidably engaging a vertical slot in the supporting-block, thus enabling swiveling and vertical movement of the holder while positively restraining endwise movement of the bar or tube during the bending operation; and a follower roller movable in a circular orbit concentric with the edge of the stationary die member, whereby the elongate shoe assumes different angular positions tangential to the peripheral edge of the stationary die member and progressively depresses the bar or tube into the inclined groove of said stationary die member.

RALPH M. SHAW, JR.
